US00D518042S

(12) **United States Design Patent** (10) **Patent No.:** **US D518,042 S**
(45) **Date of Patent:** **** Mar. 28, 2006**

(54) **PERSONAL COMPUTER**

(75) Inventor: **Masaki Kanayama**, Tachikawa (JP)

(73) Assignee: **Fujitsu Limited**, Kawasaki (JP)

(**) Term: **14 Years**

(21) Appl. No.: **29/223,445**

(22) Filed: **Feb. 15, 2005**

(30) **Foreign Application Priority Data**

Aug. 18, 2004 (JP) 2004-024671

(51) **LOC (8) Cl.** **14-02**

(52) **U.S. Cl.** **D14/318**

(58) **Field of Classification Search** D14/315-323;
D18/1, 2, 7, 11; 235/145 A, 145 R; 341/22,
341/23; 345/156, 168, 169, 172, 173; 361/680-686

See application file for complete search history.
